UNITED STATES PATENT OFFICE.

WILLIAM FREDERICK HANNES, OF DEMING, TERRITORY OF NEW MEXICO,
ASSIGNOR OF ONE-HALF TO WALTER J. BROWNING, OF DEMING, TERRITORY OF NEW MEXICO.

SMELTING-FURNACE.

SPECIFICATION forming part of Letters Patent No. 712,374, dated October 28, 1902.

Application filed July 26, 1901. Serial No. 69,820. (No model.)

To all whom it may concern:

Be it known that I, WILLIAM FREDERICK HANNES, a citizen of the United States, residing at Deming, in the county of Luna and Territory of New Mexico, have invented certain new and useful Improvements in Smelting-Furnaces; and I do hereby declare the following to be a full, clear, and exact description of the invention, such as will enable others skilled in the art to which it appertains to make and use the same.

This invention relates to improvements in smelting-furnaces, and especially to that type generally known as "vertical" or "upright" furnaces.

In the present practice of smelting ores now generally followed the fuel and material to be smelted are fed into the furnace in alternate layers or they are mixed together in certain calculated and predetermined proportions and fed into the furnace together. Air carrying the oxygen to support the combustion within the furnace is supplied in any suitable manner near the bottom and united with the carbon of the fuel, forming carbon dioxid, which passing upward through the fuel above it and being in a highly-heated state oxidizes a portion of the carbon of this fuel to form carbon monoxid, all according to well-known principles. The gases thus formed are usually drawn off and, with the addition of air, are burned in various types of engines, stoves, &c., to recover some of the heat energy, or they may be utilized in any other suitable manner.

The objects of the invention are, first, to obtain a more perfect combustion than has heretofore been possible in the methods employed; second, to produce either a reducing or oxidizing action in the furnace upon the material under treatment at the will of the operator; third, to supply sufficient fuel in the zone of fusion within the furnace to fuse or smelt any of the material supplied therein without previous calculation of the amount of fuel necessary; fourth, to subject the fluid or material to the action of the reducing-gases before drawing the same from the furnace.

With these objects in view the invention

consists in providing a furnace with one or more fuel-compartments extending downward from the upper part thereof, said compartment or compartments being in communication at its or their lower end or ends with the body portion of the furnace; further, in providing means for introducing a supply of air into the furnace thus constructed in such manner as to effect complete combustion, thereby obtaining great efficiency.

Further, the invention consists in the novel construction and arrangement of parts of a furnace, as hereinafter described and claimed.

In the accompanying drawings, in which like letters of reference indicate corresponding parts throughout, I have illustrated one form of embodiment of my invention, it being understood that other forms of embodiment thereof may be employed without departing from the spirit of the invention, and these I wish it to be understood fall strictly within the scope thereof, and in these drawings—

Figure 1 is a vertical sectional view of a furnace constructed according to my invention. Fig. 2 is an end sectional view of the same. Fig. 3 is a plan sectional view taken on the line *x* *x*, Fig. 1; and Fig. 4 is a similar view taken on the line *y* *y* of Fig. 1.

Referring to the drawings, A represents a partition-wall extending downward from the upper part of the furnace and dividing the same into a fuel-compartment B, separated from the main portion C of the furnace. This wall does not extend entirely to the bottom of the furnace, but is supported upon the arch H, leaving the lower end of the fuel-compartment B open to discharge the fuel into the portion of the furnace above the hearth where the combustion takes place. The upper end of the compartment B is provided with means *b* for supplying fuel thereto, these being preferably of the bell and funnel type, as shown in the drawings. A similar device *c* is provided for supplying ore to the main or body portion of the furnace.

While I have shown but one fuel-compartment B in the drawings, it is to be understood that there may be several of these arranged along one side of the furnace or surrounding the body portion, or in any other

suitable manner, and in many instances some such arrangement will be desirable.

In order to supply air for supporting the combustion of the fuel, I provide twyers *e*, arranged below the fuel-compartment *B* and communicating with the air-supply pipe *E*, extending partly around the exterior of the furnace. The supply of air to this latter pipe is controlled by a valve *D* of any suitable type, arranged to check or cut off the flow of air from the pipe *E'*, leading from the source of the air-supply. The twyers *e* being arranged below the compartment *B*, as above stated, are adapted to admit the air, preferably under pressure, directly to the fuel, either before or just after the time it comes in contact with the ore under treatment in the body portion of the furnace. Beyond the vertical line of fuel-supply from the compartment *B* and below the arch *H* are arranged an additional set of twyers *g*, communicating with a supply-pipe *G*, arranged upon the exterior of the furnace in a similar manner to the pipe *E*, the supply of air to this pipe being also controlled by a suitable valve. These two supply-pipes *E* and *G* are independent of each other, and hence air supplied to the twyers *e* and *g* is independently regulable. The twyers *g* are arranged so as to supply air to the ore under treatment at about the place where it contacts with the fuel-supply from the compartment *B* and also to the ore not in such contact. By this arrangement the combustion of the inflammable gases, such as carbon monoxid, issuing from the burning fuel may be regulated at will, so as to produce either a reducing or an oxidizing action within the furnace at the will of the operator. The blast from these twyers also serves to oxidize any carbon, sulfur, sulfurous vapors, or any other constituent material within the furnace. Below the twyers is arranged the hearth of the furnace, constructed in any well-known or preferred manner.

In operation the oxygen admitted through twyers *e* supports the combustion of the fuel and produces carbon dioxid, which passing through the adjacent incandescent carbon is reduced thereby to carbon monoxid. Ordinarily this carbon monoxid passes off and is afterward sometimes collected and utilized for heating purposes, whereas I admit thereto after it leaves the fuel area an additional supply of oxygen through the twyers *g*, thus serving to burn the carbon monoxid within the furnace.

As ordinarily constructed it is impossible to burn or oxidize any sulfur in copper, iron, or lead ores in blast-furnaces, because the sulfur unites with the metals and forms mattes, and therefore it has to be roasted before smelting. With my construction, for a given quantity of air or oxygen introduced through twyers *e* an equal quantity is admitted through twyers *g*, and there being no fuel beyond the vertical line of the partition it,

coming into contact with the carbon monoxid, leaving the fuel area, serves to burn it. If sulfur be present in the charge, an additional amount of oxygen or air is admitted through twyers *g* proportionate to the amount of sulfur, and the sulfur will thereby be oxidized or burned in the furnace. Therefore by manipulating the valve *F*, admitting air to the twyers *g*, an oxidizing action is produced in any degree desired. If it be closed and air is admitted only through twyers *e*, the carbon monoxid would reduce any oxids and the furnace-gases would not differ essentially from those of any other furnace.

Although I have described a specific form of furnace embodying my invention, it is to be understood that the details of construction may be varied, added to, and certain of them omitted without materially departing from the spirit of the invention, and these variations I wish it to be understood fall strictly within the scope and purview of the invention.

Having thus fully described my invention, what I claim as new, and desire to secure by Letters Patent of the United States, is—

1. In a furnace, a partition extending from the upper part thereof part way toward the bottom, whereby a fuel-compartment, having communication at its lower end with the body portion of the furnace, is formed, means for supplying fuel to the fuel-compartment, means for supplying ore to the body portion, and means for supplying oxygen to the fuel below said compartment and to the ore in the body portion above the level of the first-named oxygen-supply, substantially as described.

2. In a furnace, a partition extending from the upper part thereof part way toward the bottom, whereby a fuel-compartment, having communication at its lower end with the body portion of the furnace, is formed, means for supplying fuel to the fuel-compartment, means for supplying ore to the body portion, valve-controlled twyers for supplying oxygen to the fuel below said compartment, and independently-controllable means for supplying oxygen to the ore in the body portion above the level of the first-named oxygen-supply, substantially as described.

3. In a smelting-furnace, separate fuel and ore compartments merging together in the lower body portion, twyers below the fuel-compartment for supplying oxygen to support combustion of the fuel, additional independently-regulable twyers located above the first-named twyers admitting oxygen to the ore, substantially as described.

4. A furnace comprising separate fuel and ore compartments merging together in the lower body portion of the furnace, independently-controllable twyers for supplying oxygen to the fuel and to the ore at separate points within the furnace, independent oxygen-supply pipes without said furnace and

connected with the twyers, and means for supplying fuel and ore to the respective compartments, substantially as described.

5. In a blast-furnace, separate ore and fuel compartments merging together in the lower body portion, twyers below the fuel-compartment for supplying oxygen to support combustion of the fuel, additional twyers, located above the first-named twyers and be-

low the division-line of the compartments, to admitting oxygen to the ore, substantially as described.

In testimony whereof I affix my signature in the presence of two subscribing witnesses.

WILLIAM FREDERICK HANNES.
